UNITED STATES PATENT OFFICE.

STEPHEN BIRD, OF CAIRO, ILLINOIS.

SHOT-CASE.

931,723.

Specification of Letters Patent. Patented Aug. 24, 1909.

Application filed April 5, 1909. Serial No. 488,061.

To all whom it may concern:

Be it known that I, STEPHEN BIRD, a citizen of the United States, residing at Cairo, in the county of Alexander and State of Illinois, have invented a new and useful Shot-Case, of which the following is a specification.

The objects of the invention are, generally, the provision in a merchantable form of a device of the class above mentioned which shall be inexpensive to manufacture, facile in operation, and devoid of complicated parts; specifically, the provision of a shot case adapted to protect the bore of a fire arm against the attrition of a shot charge as the same passes out of the barrel; the provision of a shot case adapted to sweep the bore of the fire arm clean from the products of the combustion of the explosive, at each shot; the provision of a shot case adapted to hold the shot together in solid bulk as they leave the muzzle of the arm, giving the load increased penetration, and to register a closer pattern upon a target; the provision of a shot case so constructed, that, when it can no longer overcome the dispersive effort of the shot, it will separate laterally without distorting the contour of the shot charge; other and further objects being made manifest hereinafter as the description of the invention progresses.

The invention consists in the novel construction and arrangement of parts hereinafter described, delineated in the accompanying drawings, and particularly pointed out in that portion of this instrument wherein patentable novelty is claimed for certain distinctive and peculiar features of the device, it being understood that within the scope of what hereinafter is thus claimed, divers changes in the form, proportions, size and minor details of the structure may be made, without departing from the spirit or sacrificing any of the advantages of the invention.

Similar numerals of reference are employed to denote corresponding parts throughout the several figures of the drawings.

In the accompanying drawings, Figure 1 shows in longitudinal section, a shot gun shell equipped with the shot case of my invention; Fig. 2 is a transverse section on the line A B of Fig. 1; Fig. 3 is a plan of the strips which I employ in making the shot case, the ends of said strips being over-

lapped previous to their insertion into the shell.

The device forming the subject matter of this application for Letters Patent is adapted to be used in connection with shells of any construction and of any caliber. The proportion between the explosive charge and the shot charge may be varied; and it is to be understood that any form of wadding may be employed.

In order to illustrate fully the application of my device I have shown in Fig. 1 a shot gun shell and a load therefor which will prove satisfactory under average conditions. In Fig. 1 I have shown a shot gun shell comprising a paper body 1 equipped with a metal base 2 carrying a primer 3. Into this shell may be inserted a nitro powder charge, or other explosive denoted by the numeral 10. Upon the explosive charge is superposed a card wad 4, and upon the card wad 4 are superposed felt wads 5 and 6, the object of the card wad being to prevent the lubricant in the wads 5 and 6 from deteriorating the powder, and further to prevent the tearing of the wads 5 and 6 when the charge is exploded. Another card wad 7 is superposed upon the felt wads 5 and 6. Ahead of the card wad 7 in the shell is mounted the shot case of my invention with which is inclosed the shot 8, a third card wad 9 being superposed upon the shot and the shot case; at its extremity, the shell, presupposing that a paper shell has been used, is crimped upon the wad 9 as denoted by the numeral 11.

In loading a shell, I insert the explosive and the intermediate wadding thereinto. I then take two strips 12 of flexible material, preferably some textile substance, and overlap their ends slightly, as denoted by the numeral 14 in Fig. 3. The overlapping ends 14 are then inserted into the mouth of the shell and rammed down upon the wadding 10 which rests upon the powder or other explosive. When the strips 12 are thus rammed into the shell, their sides will overlap as denoted by the numeral 15 in Fig. 2. The device as thus far constructed, consists of a tube of flexible material closed at its inner end. Into the tube thus formed I insert the shot charge, the ends of the shot case being overlapped as denoted by the numeral 16. Upon these overlapping ends 16 is mounted the final card shot wad 9, and upon the wad 9 the end of the shell is

crimped in the usual manner, when a paper shell has been employed. The length and the width of the strips 12 will be determined by the caliber of the shell and by the volume 5 of the shot 8, it being understood that the said strips are to be wide enough so that their sides may overlap to form a tube, and they are to be of sufficient length so that their ends will overlap to the rear and to the 10 front of the shot charge.

When chilled shot is used in a fire arm having a cylindrical bore the attrition and consequent injury to the interior of the barrel caused by the passage of the shot, is noticeable; when a fire arm having a modified choke is subjected for a considerable period to the action of chilled shot, the injury is more marked; and when chilled shot is used in a full choke bore, the arm deteriorates 15 rapidly. This injury to the bore of fine fire arms by the use of chilled shot, is obviated when a shot case constructed in accordance with my invention, is employed, the said case serving to protect thoroughly and 20 effectively the bore of the arm against the attrition of the shot.

It is well known that nitro powders in their combustion will liberate substances which when allowed to remain in the bore 30 of the arm cause the same to become pitted in a short time. The shot case of my invention is preferably fashioned from textile material and in its passage through the bore of the arm, will sweep from the said bore, 35 any deleterious material which may have been deposited therein by the last discharge.

The shot case serves to confine the shot charge in a compact bulk as it leaves the muzzle of the arm, and when the said shot 40 case can no longer withstand the dispersive effort of the shot charge, the said case will separate laterally into two parts without unduly distorting the shape of the charge.

From the foregoing it will be seen that 45 the shot case not only serves to confine the shot but, as well, that when the time finally arrives, for the shot charge and the shot case to be separated, the separation is effected in such a manner that the pattern 50 which the shot will leave upon a target will not be rendered irregular, the shot being evenly and fairly distributed over the surface upon which it impinges.

So far as I am advised as to the state of 55 the art, it has been common heretofore to inclose shot charges in cases which must be blown apart bodily, or separated longitudi-

nally in the direction of the line of flight of the shot charge, one portion of the shot case falling to the rear of the charge, and 60 another portion thereof traveling ahead of it. Either of these expedients results in a distortion of the shot charge and I consider it of importance that my device separates laterally under the influence of the expanding shot charge. 65

I have shown and described my device as comprising two strips or patches 12 but I am aware that a greater number may be employed to advantage. 70

Having thus described my invention what I claim as new and desire to protect by Letters Patent is:

1. A device of the class described fashioned from laterally separable strips of flexible 75 material having their ends overlapped, the strips being transversely bent to form a closed case.

2. A shot case fashioned from laterally separable strips of flexible material having 80 their ends overlapped, the strips being bent transversely to bring their sides into overlapping relation throughout the length of the case.

3. A shot case fashioned from laterally 85 separable strips of flexible material having their sides overlapped throughout the length of the case to form a tube, the ends of the strips being overlapped to close the ends of the tube. 90

4. In a device of the class described, a shell; an explosive disposed within the shell; a wadding disposed within the shell upon the explosive; a shot case disposed within the shell upon the wadding; and shot disposed within the case; the said case comprising separate strips of flexible material having their sides overlapped to form a tube fitting closely within the shell, the strips at one end being overlapped upon the wadding and at the other end overlapped upon the shot. 95

5. A device of the class described fashioned from laterally separable strips of flexible material transversely bent into overlapped 105 relation, and terminally bent to form a closed case.

In testimony that I claim the foregoing as my own, I have hereto affixed my signature in the presence of two witnesses.

STEPHEN BIRD.
